UNITED STATES PATENT OFFICE.

LOUIS C. FULLER, OF NEW YORK, N. Y., ASSIGNOR TO THE ELECTRIC CUTLERY COMPANY, OF NEWARK, NEW JERSEY.

DESIGN FOR A RAZOR-HANDLE.

SPECIFICATION forming part of Design No. 21,012, dated August 25, 1891.

Application filed July 13, 1891. Serial No. 399,406. Term of patent 7 years.

To all whom it may concern:

Be it known that I, LOUIS C. FULLER, a citizen of the United States, residing in the city of New York, in the county and State of New York, have invented and produced a new and original Design for Handles for Razors, of which the following is a specification, reference being had to the accompanying drawings, illustrating my design.

My design consists of a combination of configuration and surface ornamentation. The configuration is that of the ordinary razor-handle, as shown. The surface is decorated

with a series of flat protuberances, mainly disposed in somewhat irregular lines and separated by irregular valleys or grooves, such ornamentation somewhat resembling alligator-leather.

What I claim is—

The design for handles for razors, consisting of the design substantially as shown.

LOUIS C. FULLER.
